POWDER PUFF

Ethel Hubbard, 240K Old Country Road, Hicksville, N.Y.

Filed June 2, 1960, Ser. No. 60,826

Term of patent 7 years

(Cl. D86—10)

Fig. 1 is a front perspective view of a powder puff showing my new design;

Fig. 2 is a top plan view thereof;

Fig. 3 is a side elevational view; and

Fig. 4 is an enlarged rear elevational view of the handle portion thereof, the dotted lines indicating reflecting particles.

I claim:

The ornamental design for a powder puff, as shown and described.
